UNITED STATES PATENT OFFICE.

GEORGE D. NICHOLS, OF NEW CANAAN, CONNECTICUT.

CORSET-COVER AND BUSTLE.

SPECIFICATION forming part of Letters Patent No. 359,807, dated March 22, 1887.

Application filed December 3, 1886. Serial No. 220,559. (No model.)

To all whom it may concern:

Be it known that I, GEORGE D. NICHOLS, a citizen of the United States, and a resident of New Canaan, in the county of Fairfield and 5 State of Connecticut, have invented certain new and useful Improvements in a Combined Corset-Cover and Bustle, of which the following is a specification.

The essential object of my invention is to 10 combine a bustle with the jacket-like garment usually worn by ladies over the corset, and known as a "corset-cover," thereby affording a support by means of the corset-cover, and from the shoulders of the wearer not only to 15 the bustle, but also to the articles of clothing resting thereon, the whole constituting a new article of manufacture. This object I have accomplished by the novel means hereinafter described, and illustrated in the accompanying 20 drawings, in which—

Similar letters of reference indicate corresponding parts.

The letter A designates the body of the corset-cover, which is of the usual jacket-like 30 shape, so as to rest upon the shoulders when worn, it being open in front and provided with buttons and button-holes, or other suitable fastenings at that point.

B designates the bustle combined with the 35 corset-cover. The position of this bustle is on the lower rear portion of the corset-cover below the waist-line, so that when in use the bustle takes a position opposite the hips of the wearer like an ordinary bustle, and it will be 40 readily understood that by this construction the bustle, as well as the clothing that may rest thereon, is firmly supported by the corset-cover from the shoulders of the wearer, while a very useful article of dress is thereby obtained.

The construction of the bustle B may be 45 varied according to the taste or fancy of the wearer, and in the example shown it comprises a series of stiffening-ribs, C, of whale-bone or other suitable material, which are fitted in pockets D of a skirt, E, the upper and side edges of which are fastened to the corset-cover at the proper points by stitching or other suitable means. In order to permit the skirt E, forming the body of the bustle, to be 50 washed together with the corset-cover, the ribs C should be removable from the pockets D, and in the example shown this purpose is effected by dividing the skirt in a vertical central line into two parts or sections, from which 55 the ribs may be drawn in an inward direction through the opening F left between the sections. When the skirt E is made as last described, it is provided with cords G or the like for closing the opening F.

In order to permit of firmly holding the bustle B to the waist, the corset-cover is provided with waistbands I on the inner portion thereof, as shown in Fig. 3, said bands being adapted to go around the waist and be fastened on the 70 front of the wearer.

It should be understood that what I have 75 termed a "corset-cover" may be any jacket-like garment, whether worn to cover the corset or otherwise.

I am aware that a garment-supporter has heretofore been made with an enlarged lower portion extending entirely around the article, and I do not claim such as my invention, the important feature of which is to arrange 80 a bustle in the lower rear portion of the cover for a corset, leaving the front portion of said cover in its natural state unaffected by the bustle.

What I claim as new, and desire to secure 85 by Letters Patent, is—

A corset-cover, A, having waistbands I on the interior thereof, in combination with a bustle, B, formed in two sections on the lower rear portion of said cover, and provided with 90 cords G, substantially as shown and described.

GEORGE D. NICHOLS.
